UNITED STATES PATENT OFFICE

2,477,097

ROTARY GUIDE

Leon E. Simmons, Claremont, N. H., assignor to
 Joy Manufacturing Company, a corporation of
 Pennsylvania

Application April 2, 1945, Serial No. 586,067

11 Claims. (Cl. 308—187)

1

This invention relates to rotary guide bearings, and more particularly to an improved guiding means for a cutter chain at the outer end of a mining machine cutter bar for guiding the cutter chain about the curved end of the bar.

In coal cutting machines an endless cutter carrying cutter chain is guided for circulation about the margin of a relatively narrow elongated plane cutter bar, and oftentimes a rotary guide is arranged at the outer end of the bar for guiding the cutter chain as it passes around the curved end of the bar. The rotary guide may be either a chain guide sprocket or a guide roll, and, due to the location of the guide at the outer end of the cutter bar, it is extremely difficult to provide adequate bearing means for the guide as well as adequate lubrication for the guide bearings. It is also desirable to provide a dirt seal for the guide bearings, and, in the event some dirt does attain access to the internal bearing structure, it is desirable to provide a space in which such dirt may remain when it is thrown off from the bearings, instead of having to be continuously carried around and around and cause wear.

An object of the present invention is to provide an improved bearing means for a rotary guide. Another object is to provide an improved guiding means associated with a cutter bar for guiding a cutter chain as it passes around the curved end of the cutter bar. A further object is to provide an improved bearing mounting for a rotary chain guide at the outer end of a mining machine cutter bar. A still further object is to provide an improved bearing mounting for a rotary guide wherein bearings are provided for the inner and outer surfaces of the guide. Still another object is to provide an improved guide bearing having improved lubricating means and improved dirt collecting means. Yet another object is to provide an improved guide bearing of the roller chain type. A still further object is to provide an improved rotary chain guide constructed in an improved manner to reduce the possibility of access of dirt to the bearings. Still another object is to provide an annular rotary guide having improved bearing means coaxing with the inner and outer surfaces of the guide, whereby the latter is journaled in an improved manner. These and other objects and advantages of the invention will, however, hereinafter more fully appear.

In the accompanying drawings, there are shown for purposes of illustration two forms which the invention may assume in practice.

In these drawings:

Fig. 1 is a view, partially in plan and partially 55 opposite to that which is engaged by the cutter

2

in horizontal section, of the outer extremity of a cutter bar equipped with an illustrative form of the improved guide bearing.

Fig. 2 is a view in vertical section taken substantially on line 2—2 of Fig. 1 and on a larger scale.

Fig. 3 is a view similar to Fig. 1, showing a modified form of guide bearing.

Fig. 4 is a vertical sectional view taken substantially on line 4—4 of Fig. 3 and on a larger scale.

10 In both illustrative embodiments of the invention, the improved guide bearing is associated with a narrow elongated plane cutter bar 1 having straight parallel side guideways 2, 2 and a curved guideway 3 at the curved outer end of the cutter bar, the curved guideway 3 joining the parallel side guideways 2. An endless cutter chain 4 is guided for circulation in the bar guideways about the margin of the cutter bar and includes, as shown, conventional chain blocks 5 pivotally connected at 6 to connecting strap links 7. The cutter bar includes upper and lower plates 8, 8 and intermediate side bars 9, 9, the bars and plates being rigidly connected together as by bolts 10. The side bars 9 are arranged in laterally spaced relation to provide a longitudinal recess 11 therebetween at the longitudinal center of the cutter bar, and the outer ends of the side bars are beveled at 12. The chain blocks 5 of the cutter chain carry usual cutter bits 13 held on the chain blocks 5 by usual set screws 14.

Now referring to the improved rotary guide bearing shown in its preferred form in Figs. 1 and 2, it will be observed that an annular guide roll 15 surrounds a generally circular bearing support 16 arranged between and recessed within the bar plates 8, 8 and rigidly secured to the bar as by bolts 17. Encircling the circular bearing support 16 between the outer, generally cylindrical surface 18 of the latter and the inner cylindrical surface 19 of the guide roll 15 is an endless roller type chain bearing 20. This chain bearing consists of a series of bearing rollers 21 mounted on pins 22 connected by pivoted straps 23. Arranged at the opposite sides of the guide roll 15 are thrust rings 24 having annular portions received in annular grooves in the inner surfaces of the bar plates 8 and held against bodily rotation with respect to the bar plates by dowel pins 25. These thrust rings absorb the end thrust of the guide roll and chain bearings, and constitute dirt seals. The circular bearing support 16 has a chamber 26 for receiving lubricant, and a passage 27 conducts the lubricant from the chamber to the roller chain bearing. At the side of the bearing support 16

chain is an inwardly directed recess 28 having curved sides for receiving dirt thrown off the chain bearing, and, as the roller chain passes across this recess, it may whip inwardly, and shake off any dirt which might be carried thereon. Engaging the outer periphery 29 of the side of the guide roll more remote from the free end of the cutter bar is a bearing block 30 having a rectangular portion 31 fitted within the recess 11 between the side bars 9 of the cutter bar, and this bearing block also has inclined surfaces 32 engaging the beveled surfaces 12 on the outer ends of the side bars 9. This bearing block has recesses 33 formed in its opposite faces and connected by a passage 34, and these recesses are adapted to contain a lubricant for the bearings. The lubricant recesses 26 and 33 are provided with filler plugs 35 and 36 conveniently located at the opposite sides of the cutter bar to permit replenishing of the lubricant supply.

In the modified embodiment shown in Figs. 3 and 4, the cutter bar and cutter chain structure is similar to that above described. In this instance, surrounding a circular bearing support 37 arranged within the cutter bar between the bar plates are bearing sleeves 38 by means of which a guide sprocket 39 is journaled. The bearing support 37 has formed in its opposite faces recesses 40 connected by a passage 41, and these recesses are adapted to contain a lubricant for the bearings. Relatively narrow passages 42 connect the recesses 40 with the inner surfaces of the bearing sleeves to permit free lubricant flow, and these passages also provide recesses for collecting any dirt thrown off from the bearing sleeves. As shown, the guide sprocket has sprocket teeth 43 adapted to project between the ends of the chain blocks and between the strap links in the manner shown. A guide block 44 engages at 45 the outer cylindrical surface of the guide sprocket at the side of the latter more remote from the free end of the cutter bar, and this member is centrally arcuately grooved at 46 to permit the passage of the sprocket teeth 43 past the guide block. The guide block 44 is similarly positioned with respect to the side bars of the cutter bar as the block 30, and has similar lubricant recesses.

From the foregoing, it will be evident that, by the provision of the improved bearing structure for the rotary guide, the latter is journaled at its inner and outer surfaces in an improved manner. By the provision of the improved guide structure, not only is the rotary guide adequately supported at its inner and outer surfaces, but also improved lubricating means is associated with the bearings. By the provision of the dirt collecting recess in the inner side of the central bearing support, any dirt which might attain access to the bearings may be collected at a point where it will do no harm to the bearing surfaces. By the provision of the roller type bearing chain in the preferred embodiment, not only is the rotary guide adequately journaled, but also the roller bearing chain, due to its construction, has a whipping action as it passes across the dirt collecting recess so that any dirt collected on the bearing is effectively thrown off. In each illustrative embodiment of the invention an annular member (15 or 39) engaged by the cutter chain is rotatable upon interior bearings which turn with it (20 or 38) and in each embodiment a stationary thrust bearing surface-providing element (30 or 44) rotatably supports the annular member engaged by the chain, and if there is any play upon the interior bearings, so to speak, there is provided support and guiding and thrust absorption

by the members 30 or 44. The further manners of use and other advantages of the improved guide bearing will be clearly apparent to those skilled in the art.

5 While there are in this application specifically described two forms which the invention may assume in practice, it will be understood that these forms of the same are shown for purposes of illustration, and that the invention may be modified and embodied in various other forms without departing from its spirit or the scope of the appended claims.

What I claim as new and desire to secure by Letters Patent is:

1. In a rotary guide, an annular rotary guide member having concentric inner and outer bearing surfaces and with which an element to be guided is engageable, and a bearing mounting for said guide member having inner bearing means engaging said inner bearing surface and outer bearing means engaging said outer bearing surface, said outer bearing means engaging said outer bearing surface only at points spaced circumferentially of said guide member from the points of engagement with the latter of said element to be guided thereby.

2. In a rotary guide, an annular rotary guide member having concentric inner and outer bearing surfaces and with which an element to be guided is engageable, a bearing mounting for said guide member having inner bearing means engaging said inner bearing surface and outer bearing means engaging said outer bearing surface, said outer bearing means engaging said outer bearing surface only at points spaced circumferentially of said guide member from the points of engagement with the latter of said element to be guided thereby, and means associated with said inner and outer bearing means for supplying lubricant to said bearing surfaces.

3. In a rotary guide, an annular rotary guide member having concentric inner and outer bearing surfaces and with which an element to be guided is engageable, a bearing mounting for said guide member having inner bearing means engaging said inner bearing surface and outer bearing means engaging said outer bearing surface, said outer bearing means engaging said outer bearing surface only at points spaced circumferentially of said guide member from the points of engagement with the latter of said element to be guided thereby, and means provided by one of said inner and outer bearing means forming a dirt collecting recess for receiving dirt thrown off of one of the bearing surfaces.

4. In a rotary guide, an annular rotary guide member having concentric inner and outer bearing surfaces and with which an element to be guided is engageable, a bearing mounting for said guide member having inner bearing means engaging said inner bearing surface and outer bearing means engaging said outer bearing surface, said outer bearing means engaging said outer bearing surface only at points spaced circumferentially of said guide member from the points of engagement with the latter of said element to be guided thereby, and means provided by said inner bearing means forming a lubricant receiving recess for supplying lubricant to the inner bearing surface.

5. In a rotary guide, an annular rotary guide member having inner and outer concentric bearing surfaces, a bearing mounting for said guide member having inner bearing means engaging said inner bearing surface and outer bearing

means engaging said outer bearing surface, means provided by said inner bearing means forming a lubricant receiving recess for supplying lubricant to the inner bearing surface, and a dirt collecting recess also provided by said inner bearing means, the lubricant flowing from said lubricant receiving recess through said dirt collecting recess to the inner bearing surface.

6. In a rotary guide, an annular rotary guide member having concentric inner and outer bearing surfaces and with which an element to be guided is engageable, a centrally located bearing support which is surrounded by said guide member, bearings supported by said bearing support and engaging the inner bearing surface of said guide member, and a bearing member arranged externally of said guide member and engaging said outer bearing surface of said guide member only at points spaced circumferentially with respect to said guide member from the points of engagement with the latter of said element to be guided thereby.

7. In a rotary guide, spaced outer plates, a rotary guide member arranged between said plates and having a cylindrical bearing surface with which an element to be guided is engageable, a cylindrical bearing support arranged between and secured to said plates, a bearing interposed between said support and said bearing surface, and an additional bearing element arranged between and secured to said plates and engaging said guide member only at points spaced circumferentially with respect to said guide member from the points of engagement with the latter of said element to be guided thereby.

8. In a rotary guide, a rotary guide member having a cylindrical bearing surface, a cylindrical bearing support, and a roller bearing chain interposed between said support and said bearing surface, said bearing support having a recess and said roller chain, as it moves across said recess, having a whipping action which tends to throw off any dirt on said chain, and said recess collecting the dirt so thrown off.

9. In a rotary chain guide, the combination with a guide bar having parallel outer plates and parallel side bars spacing said plates and providing a recess at the longitudinal center of the guide bar, of a rotary guide at the outer end of said guide bar intermediate said outer plates for guiding a chain as it passes around said guide bar, and a bearing block positioned at the outer ends of said side bars between said plates and hav-

ing a portion projecting within said recess, said block having a bearing surface engaging the outer bearing surface of said rotary guide.

10. In a rotary chain guide, the combination with a guide bar having parallel outer plates and parallel side bars spacing said plates and providing a recess at the longitudinal center of the guide bar, of a rotary guide at the outer end of said guide bar intermediate said outer plates for guiding a chain as it passes around said guide bar, and a bearing block positioned at the outer ends of said side bars between said plates and having a portion projecting within said recess, said block having a bearing surface engaging the outer bearing surface of said rotary guide, and a bearing support arranged centrally within said rotary guide between said bar plates and providing a bearing at the inner surface of said rotary guide.

11. In a rotary chain guide, a rotary guide member having lugs to coact with recesses in a chain, a generally cylindrical bearing support, bearing sleeves turning with said rotary guide member and engaging said bearing support, and a stationary bearing block having spaced guide member bearing-providing portions between which said lugs pass and which are adapted to carry a portion of the bearing load imposed by said rotary guide member when the latter is driven by a chain.
